UNITED STATES PATENT OFFICE.

ROBERT T. POPLIN AND WILLIAM F. FERGUSON, OF BUTTERFIELD, MISSOURI.

AUTOMATIC TRAIN-STOP.

1,171,539.

Specification of Letters Patent. Patented Feb. 15, 1916.

Application filed July 3, 1915. Serial No. 37,907.

To all whom it may concern:

Be it known that we, ROBERT T. POPLIN and WILLIAM F. FERGUSON, citizens of the United States, residing at Butterfield, in the 5 county of Barry and State of Missouri, have invented certain new and useful Improvements in Automatic Train-Stops, of which the following is a specification, reference being had to the accompanying drawings.

10 Our invention relates to automatic devices for stopping trains, and particularly to means for stopping trains in case of derailment.

Under the present system, when trains are 15 derailed, the train runs forward over the ties, tearing up the track with dragging trucks until the train turns over or until the train line comes apart or becomes otherwise disconnected.

20 The primary object of our invention is to provide means for automatically venting the air of the train pipe in case of derailment or in case of the breaking of a truck or axle beneath the car so that the car drops, 25 and in this connection to provide a vent valve actuating member which is yieldably supported beneath the car in position to be engaged by the rails of a track when either the car is derailed or the truck breaks, this 30 vent valve actuating member being yieldably supported as above described so that under these circumstances it will move upward and open a vent valve in the train pipe, immediately applying the brakes in 35 the same manner as brakes are applied when an air hose bursts.

A further object of the invention is to so construct the vent valve actuating member that it will be sure to be actuated upon the 0 derailment or dropping of a car, and further so construct it that the connection to the vent valve may be readily adjusted so that it may correspond to the different positions of the air line of different cars.

5 Other objects will appear in the course of the following description.

Our invention is illustrated in the accompanying drawings, wherein:

Figure 1 is a fragmentary diagrammatic 0 end elevation of a car showing our invention applied thereto, the rails upon which

the car runs being in section; Fig. 2 is a like view to Fig. 1 but showing the wheels derailed and showing the operation of the train stopping device; Fig. 3 is an enlarged 55 sectional view of the lower end of one of the hangers showing the manner in which the valve actuating member is supported; and Fig. 4 is a detailed view of the valve.

Referring to the drawings, A designates 60 a railway car of any suitable construction, and B the rails upon which the car runs. Mounted upon the under side of the car and bolted to the sills or bottom of the car in any suitable manner are the depending 65 hangers 2. These hangers are approximately U-shaped in the preferable form of our invention, and the legs at the lower ends of the hangers extend parallel to each other a certain distance, as to a point 3, and then 70 diverge upward and outward and at their upper ends are flanged at 4 for the attachment to the bottom of the car.

Disposed in the lower ends of the hangers 2 and supported between the parallel portions of the legs thereof for vertical movement is a valve actuating member 5 having the form of a bar extending transversely of the car. The bar 5 is supported by these hangers at a height from three to six inches 80 above the track rails, and extends transversely across the track and beyond the rails. Preferably disposed between the legs of each hanger just below the point 3 is a filling piece 6 which is illustrated as bolted 85 to the hangers by means of a bolt 7, and disposed between this filling piece and the bar 5 is a coiled spring 8 which resists any upward movement of the bar relative to the hangers. This coiled spring may be supported in any suitable manner, but as illustrated a depending pin 9 is formed upon the filling piece 6 and extends through an opening 10 in the bar 5. These pins support the springs 8 from detachment, but any 90 other suitable means for supporting the springs may be provided.

Disposed beneath the car in the usual or ordinary manner is a train pipe 11 which forms part of the air brake system. This 10 train pipe is conventionally shown in Figs. 1 and 2, and inasmuch as the construction,

arrangement, and operation of air brake train pipes is well known no further description is necessary. Disposed within the length of the train pipe beneath each car is 5 a vent valve section 12 within which is disposed a vent valve 13. This vent valve may be constructed in any usual and ordinary manner, and we do not wish to limit ourselves to the conventional showing of such 10 an air valve as is illustrated in the accompanying drawings. This air valve is provided with the outwardly projecting arm 14. Operatively connected to this arm is a rod preferably formed in two sections 15 ad- 15 justably connected to each other by means of a turn buckle 16. Any other means for adjusting the length of this rod may be used, however. It has been found in practice that this form of connection is particu- 20 larly convenient and permits the ready and accurate adjustment of the connecting rod for length. The lower end of the connecting rod is angularly bent, as at 17, and is adapted to be engaged with any one of a 25 plurality of openings 18 formed in the bar 5. These openings 18 permit the rod 15 to be adjusted laterally so as to accommodate the device to any lateral position of the train pipe relative to the longitudinal axis 30 of the car body. As illustrated, the angular end of the connecting rod is held from detachment with the bar 5 by means of a cotter pin 19. The bar 5 is prevented from longitudinal movement in the hangers 2 by 35 means of bolts or pins 20.

The operation of this invention will be obvious to those skilled in the art. Under normal circumstances the hangers 2 support the bar 5 at a height of from three to 40 six inches above the rails B. In case, however, of a breakage of a car truck, a car axle, or in case of derailment, the car will drop relative to the track and one or both ends of the bar 5 will be lifted. This will 45 shift the connecting rod 15 and rotate the valve 13 to vent air from the train pipe whereupon the brake will automatically be applied and the train come to a stop much sooner than would be the case were our 50 device not applied thereto. Under ordinary circumstances the train, after derailment, may run some distance before the train pipe is ruptured so as to cause the application of the brakes. With our mechanism, how- 55 ever, the derailment of a train or any other accident which will cause the car to drop relative to the rails will cause an immediate application of a brake and bring the train to a standstill before great damage has been 60 done.

While we have shown a simple and effective form of our invention, we do not wish to be limited to all the details as it is obvious that these may be modified in many

ways without departing from the spirit of 65 the invention.

Having thus described our invention, what we claim is:

1. The combination with a car and an air brake system including a train pipe and a 70 vent valve, of hangers supported from the car body, a valve actuating member loosely supported for vertical movement in said hangers and extending transversely of the car and beyond and above the rails over 75 which the car travels, said member being operatively connected with the vent valve to open the vent valve upon contact of the member with the rails caused by a descent of the car body relative to the rails. 80

2. The combination with a car and an air brake system including a train pipe and a vent valve, of hangers depending from the car, a transversely extending bar loosely supported in said hangers for vertical movement and extending beyond the rails upon which the car runs, said hangers supporting the bar normally in spaced relation to the rails, springs urging the bar downward toward the lower ends of the hangers and 90 resisting accidental upward movement of the bar, and an operative connection between said bar and the vent valve. .

3. The combination with a car and an air brake system including a train pipe and a 95 vent valve, of hangers depending from the car, a transversely extending bar loosely supported in said hangers for vertical movement and extending beyond the rails upon which the car runs, said hangers supporting 100 the bar normally in spaced relation to the rails, springs urging the bar downward toward the lower ends of the hangers and resisting accidental upward movement of the bar, and an operative connection between 105 said bar and the vent valve, said connection being adjustable for length.

4. The combination with a car and an air brake system including a train pipe and a vent valve, of hangers depending from the 110 car, a transversely extending bar loosely supported in said hangers for vertical movement and extending beyond the rails upon which the car runs, said hangers supporting the bar normally in spaced relation to 115 the rails, springs urging the bar downward toward the lower ends of the hangers and resisting accidental upward movement of the bar, and an operative connection between 120 said bar and the vent valve, said connection being adjustably engageable with the bar at a plurality of points.

5. The combination with a car and an air brake system including a train pipe and a vent valve, of supporting members depending from the car, a bar extending transversely of the car and carried by said supporting members and having free vertical 125

movement, means yieldingly resisting the vertical movement of the car, and means connecting the bar to the vent valve comprising a turn buckle and rods engaged by 5 the turn buckle and respectively with the bar and vent valve.

In testimony whereof we hereunto affix

our signatures in the presence of two witnesses.
